UNITED STATES PATENT OFFICE.

AUGUSTINE A. DELANO, OF BROCKTON, MASSACHUSETTS, ASSIGNOR OF
ONE-HALF TO FRED DREW, OF BROCKTON, MASSACHUSETTS.

SHOE TREE OR STRETCHER.

SPECIFICATION forming part of Letters Patent No. 772,873, dated October 18, 1904.

Application filed January 14, 1904. Serial No. 188,984. (No model.)

To all whom it may concern:

Be it known that I, AUGUSTINE A. DELANO, of Brockton, in the county of Plymouth and State of Massachusetts, have invented certain new and useful Improvements in Shoe Trees or Stretchers, of which the following is a specification.

This invention relates to shoe trees or stretchers which are intended to be used by the wearer of a pair of shoes to exert longitudinal pressure on the interior of the upper between the heel and toe portions for the purpose of eradicating wrinkles and of supporting the upper so that it may be conveniently cleaned, polished, &c.

The invention has for its object to provide a two-part tree or stretcher adapted to be quickly and conveniently engaged with the upper and to effectively support the flexible forward portion thereof in such manner as to give the same a smooth surface and enable it to be readily cleaned and dressed, one of the parts of the device constituting a handle which projects from the upper in convenient position to be held by the operator.

The invention consists in the improvements which I will now proceed to describe and claim.

Of the accompanying drawings, forming a part of this specification, Figure 1 represents a top plan view of my improved shoe tree or stretcher, showing the same adjusted for insertion in a shoe. Fig. 2 represents a longitudinal section on line 2-2 of Fig. 1. Fig. 3 represents a longitudinal section of a shoe and a side elevation of my improved tree or stretcher partially engaged therewith, the said figure also showing the tree or stretcher in dotted lines adjusted as shown in Figs. 1 and 2. Fig. 4 represents a longitudinal section of the shoe and tree, showing the tree fully engaged with the shoe.

The same reference characters indicate the same parts in all the figures.

In the drawings, *a* represents the fore part of my improved tree, the same being formed to enter the fore part of the upper of a shoe *b*, the upper surface of the fore part *a* being curved crosswise to afford a support for the

median portion of the vamp when the tree is 50 fully engaged with the shoe, as shown in Fig. 4. The fore part *a* is so slender, however, that it is adapted to move freely endwise into and out of the upper without material frictional resistance. In the rear portion of the 55 fore part *a* is formed a vertical slot *a'*, which extends forward from the rear end along the median line of the fore part. The upper portion *a*² of the inner end or bottom of the slot *a'* constitutes a stop the function of which 60 will be presently described.

c represents a lever which extends through the slot *a'* and is connected by a pivot-pin *d* with the portions of the forepart forming the sides of said slot. The lever comprises an 65 outer arm 2 and an inner arm 3, said arms extending from the pivot *d* at different angles, so that a straight line drawn from the pivot through the center of the outer end of the outer arm would stand at an obtuse angle 70 with a line drawn from said pivot through the center of the outer end of the inner arm, as indicated by dotted lines in Fig. 2. The forward edge of the outer arm 2 has a protuberance formed at 75 30 to bear upon the stop *a*².

The form and relative arrangement of the above-described parts is such that when the outer arm 2 is moved away from the stop *a*², as shown in Fig. 1, the inner arm 3 projects forward under the fore part *a* and is in position to be conveniently inserted in the upper with the fore part, as indicated by dotted lines in Fig. 3, the outer arm at the same time extending substantially in alignment with the fore part *a*. 80 When, however, the outer arm is swung forward toward the stop *a*² after the stretcher has been inserted in the upper, the inner arm is swung downward and backward, so that its outer end comes to a bearing simultaneously 85 on the rear end of the inner sole and the adjoining part of the counter portion of the upper before the fore part has reached the extreme of its forward movement and before the outer arm comes to a bearing on the stop 90 *a*², as indicated by full lines in Fig. 3. A continuation of the forward movement of the outer arm causes the fore part *a* to be forced

forward against the toe portion of the upper and upward against the median portion of the vamp, so that when the outer arm reaches the stop a^2 the fore part a is pressed firmly forward against the said toe portion and upward against the vamp, the pressure being sustained by the relatively rigid lower portion of the counter of the shoe adjoining the inner sole and heel. The stretcher is therefore given a practically rigid support when in the position shown in Fig. 4 by the said counter portion, so that there is no liability of the backward yielding of the stretcher, as would be the case if the inner arm 3 had a bearing on the upper at a point considerably above the sole, or, in other words, if the inner arm 3 did not bear simultaneously on the inner sole and on the adjoining counter portion of the upper. The importance of this relatively rigid support for the inner arm 3 will be appreciated when it is borne in mind that the said inner arm not only supports the forward pressure of the fore part against the toe of the upper, but also the upward pressure of said fore part against the vamp.

The outer arm 3 when in the position shown in Fig. 4 projects from the upper in such direction that it constitutes a convenient handle whereby the operator may manipulate the shoe when cleaning and dressing the same.

It will be seen by reference to Fig. 4 that when the tree is adjusted in operative position in the shoe the only parts of the stretcher that are in contact with the sole are the rear end of the arm 3 and the forward end of the fore part a . The pressure exerted between the heel and the toe portions tends to straighten the sole and prevent it from curling upwardly

when it is taken off in a wet or damp condition, the upper surface of the fore part at the same time removing wrinkles from the upper.

I claim—

A shoe tree or stretcher comprising a fore part adapted to be seated on the interior of the toe portion of an upper and having a longitudinal slot in its rear portion, the outer portion of the bottom of said slot constituting a stop, and a lever jointed to the rear portion of the fore part and extending through the slot, the said lever having an outer arm the forward edge of which is formed to co-operate with the said stop, and an inner arm constituting a heel part, projecting from the fore part at an angle with the outer arm, the arrangement of the arms relatively to each other and to the stop being such that when the outer arm is thrown backward from the stop, the inner arm projects forward under the fore part, and is adapted to be inserted with the fore part in the upper, and when the outer arm is thrown forward against the stop the inner arm is swung downward and backward and caused to bear simultaneously on the rear end of the inner sole and the adjoining portion of the upper and exert forward and upward pressure on the fore part, said pressure being sustained by the relatively rigid lower part of the counter portion of the upper.

In testimony whereof I have affixed my signature in presence of two witnesses.

AUGUSTINE A. DELANO.
